REMOVABLE WINDOW SASH

Davis Forbes Holmes, Atlanta, Ga., assignor of
one-half to Minnie Roberta Stork, Atlanta, Ga.

Application June 8, 1949, Serial No. 97,803

4 Claims. (Cl. 20—52.2)

1

This invention relates to windows and more particularly to a sash structure constructed so as to be readily removed from a window frame, and it consists in the constructions, arrangements and combinations herein described and claimed.

It is a particular object of the invention to provide a sash structure which may readily be removable from a casement frame from the inside of a dwelling, but which cannot be removed from the exterior thereof.

It is also an object of the invention to provide a sash of the kind described in which a wedging block is employed to retain the sash in a locked position within the frame and said bolt in addition functions to maintain the sash within the frame in such a manner as to effect an air-tight seal between the sash and frame to prevent ingress of cold air and egress of hot air during cold weather.

A still further object of the invention is the provision of novel constructions of one piece channel members which may be installed in a window framing without the use of fastening means such as nails or screws and which are retained in operative position with the sliding sash by means of sliding wedging bolts, the latter being operatively engaged with elastic cushion elements carried by portions of one of the channel members, said bolts having a locking means for preventing unauthorized removal of either of the sashes.

Additional objects, advantages and features of invention will be apparent from the following description considered in conjunction with the accompanying drawings wherein:

Figure 1 is a front elevation of a window constructed in accordance with the present invention;

Figure 2 is an enlarged fragmentary cross section on the line 2—2 of Figure 1;

Figure 3 is a vertical section on the line 3—3 of Figure 2;

Figure 4 is a fragmentary perspective view of one of the channel members of the structure;

Figure 5 is a perspective view of one of the wedging blocks; and

Figure 6 is a cross section on the line 6—6 of Figure 5 illustrating the lock mechanism of the wedging block.

Reference is first made to Figure 1 of the drawings, wherein there is shown a window frame structure 10 consisting of a pair of window sashes 11 and 12, the latter being vertically slidable in respective one piece channel members 13 and 13'.

2

at the sides of the window frame stiles 14 and 14' as best seen in Figure 2.

The exterior of the window is indicated at 15 while the interior thereof is represented by the reference character 16. The exterior of the frame embodies a mullion 17 at respective sides suitably mortised with an upright strip 18 at one side, which has a recess 19 for reception of a laterally extended flange 20 of a channel member 13. At the opposite side of the frame, an upright strip 21 is mortised into the frame and includes an inwardly directed flange 22 for support of a channel 13'.

The interior of the window frame comprises an upright stile 23 at one side having a vertical channel or recess 24 for accommodation of a flange 25 corresponding to the flange 20 previously described, the channels or recesses and the flanges being in alignment. At the opposite side of the frame a vertical stile 26 is provided having a rabbet 27 for reception of a lateral flange 28 of the channel 13'.

Upon the interior of the window frame indicated at 16 suitable finishing strips 29 and 30 are secured by mortising or otherwise and additionally secured by "Allen" headed screws 31.

As may be best seen in Figure 4, the channels 13' comprise a single stamping of sheet metal, such as aluminum, having a pair of sash channels 31 connected by a parting strip 32 which is directed inwardly toward the stile 14. At respective sides of the channel respective flanges 20' and 25' are formed and each of these flanges is provided with an elastic strip 34. The elastic strips 33 and 34 are preferably formed of synthetic rubber, such as "neoprene" which has the characteristics of maintaining elasticity and therefore admirable for effecting an airtight condition between the window frame and the window sash, as will be described.

The channel 13' is provided with a plurality of pins 35 adapted to register with respective bores 36 formed in the upright stiles 14 and interior framing 37 of the frame. The provision of the pins 35 and bores 36 insures guidance of the lateral displacement of the channel 13' as will be required in the removal of the sash 11 and 12 as will be described.

Upon the window stile 14' are mounted respective pairs of transverse guide strips 38 spaced apart a distance to receive therebetween a wedging block 39, these strips 38 being spaced to slidably receive the blocks to engage the channel member 13' so as to force the sashes to the opposite channel 13 to provide an effective air-tight

relation between the sash members and the frame.

Attention is now invited to Figures 5 and 6 of the drawings wherein the block 39 is shown in detail. The block 39 is of elongated form, the forward end being tapered as at 40, the outermost end of the block 39 being hollow as at 41 (see Figure 6) and in which there is mounted a transverse sleeve 42 having a slot 43 through which an arm 44 of a lock 45 may pass for projecting a bolt 46 into a passage 47 formed in the stile 14. A closure plate 48 closes the hollow end of the block and includes an opening 49 for admission of a suitable key for actuating the bolt 46.

The channel 13 is identical in construction with the channel 13' just described, except that the guide pins 35 are omitted.

In the present instance, I have shown the finishing strip 30 as having a pair of openings 50 aligned with respective pairs of guide strips 38 for receiving the block 39 so that a bearing contact may be had between the adjacent side of the block and the elastic strips 33 and 34, and of course, the width of the block is such as to apply lateral pressure and a compressive force upon the strips 33 and 34 and thus exert lateral pressure upon the sash members 11 and 12 for retaining the latter in a tight engagement with the channels 13 and 13'. Initially, there is a slight clearance between the stile 14 and the channel 13' but this will be compensated for by the forward tapered end 40 of the block during its inward passage so that the channel 13' will be properly positioned with respect to the sash members.

We will assume that the sash members 11 and 12 are in their secured positions within the frame 10 with the blocks 39 in their locked positions. In order to remove the sash from the frame both sash members are moved to their lower positions and the locking bolts 46 are retracted so that the blocks 39 may be withdrawn from the frame 10. The top block 39 will be the first to be removed so that the sash 12 may be lowered by gravity after which the lower block 39 may be withdrawn. The channel member 13' is thus free to move laterally by exerting a corresponding pressure on the frames 11 and 12, thereby moving the sash from the channel member 13 and may then be completely removed from the frame, so that the sash may be washed or painted. The channel 13' will be fully seated within the frame so that the sash may be readily returned to seated engagement in the channel member 13. The blocks 39 are then replaced in the openings 50 and between the guide strips 38, the tapered end 40 of the wedging blocks enabling ready passage over the resilient strips 33 and 34. When the blocks 39 are fully engaged in the frame, the sash 11 and 12 will again be seated within the channels 13 and 13' firmly held against rattling and by virtue of the elastic strips 33 and 34 an air-tight seal is provided. The bolts 46 are then projected into respective bores 47 and the sash are thus secured against removal. It will be seen that with the wedge blocks 39 in position within the frame lateral movement of the sash is not possible, and the

sash can only be removed after removal of said blocks.

While I have shown and described a preferred form of the invention, this is by way of illustration only and I consider as my own all such modifications in construction as fairly fall within the scope of the appended claims.

What I claim:

1. A removable window sash comprising a window frame, vertical channel members at respective sides of the window frame, one of said channel members being fixed in said frame, the other channel member being laterally movable, a sash positioned for vertical sliding movement in said channels, and a wedging block movable transversely across said movable channel member exerting lateral pressure thereon in the direction of the fixed channel member, said movable channel member having resilient means at points of contact with said wedging block.

2. A window frame comprising upright side stile members, a channel member in each of the stile members, each channel having a pair of vertically extended recesses, the recesses of one channel member being in alignment with the recesses of the other channel member, each channel having a vertical parting strip positioned between said recesses and further having lateral extensions at the outer vertical edges thereof, a resilient strip secured to said parting strip and said lateral extensions, one of said channel members being fixed in one of said stile members, the other of said channel members being laterally movable within the other of said stile members, said last named stile member having spaced bores formed therein, pins carried by said laterally movable channel and disposed in a respective bore, transverse spaced guide bars on said last named stile member, a wedge block slidable transversely between each pair of guide bars and having a portion exposed exteriorly of the last named stile member, said wedge blocks having a width to engage the resilient strips of the laterally movable channel member and force said channel member in the direction of the fixed channel member and a sash mounted within respective aligned pairs of recesses frictionally held against sliding movements.

3. The structure of claim 2 in which said wedge blocks each include a lock bolt operable to prevent withdrawal of the wedge blocks.

4. The structure of claim 2 in which the wedge block has a tapered forward end permitting ready passage to fully engaged position beyond the resilient strips.

DAVIS FORBES HOLMES.
